ANDREW B. CLAYTON, OF UNION, NEW JERSEY, ASSIGNOR TO THE SINGER MANUFACTURING COMPANY, OF ELIZABETH, NEW JERSEY, A CORPORATION OF NEW JERSEY

LOOPER-ACTUATING MECHANISM FOR SEWING MACHINES

Original application filed January 28, 1928, Serial No. 250,111. Divided and this application filed October 11, 1928. Serial No. 311,736.

This invention relates to sewing machines, more particularly of the cylinder-bed chain-stitch type, and has for an object to provide a sewing machine with simplified and compact looper-actuating mechanism adapted to be housed in a restricted space as within the sewing machine cylinder-bed.

The looper mechanism, in its preferred embodiment, comprises a sliding and rocking looper-shaft extending lengthwise of the cylinder-bed below the main-shaft. Rocking movements of the looper-shaft are derived from a long eccentric on the main-shaft, which eccentric is slidably embraced by a forked arm fixed to the looper-shaft. Sliding movement of the looper-shaft is derived from a bell-crank and link connection with the needle-bar operating rock-shaft, which, in turn, is actuated by a crank-and-pitman connection with the main-shaft.

The invention will be better understood by referring to the accompanying drawings in which Fig. 1 is a side view, in section, of the entire sewing machine, and Fig. 2 is a section on the line 2—2, Fig. 1.

In the preferred embodiment of the invention illustrated, 1 represents the standard of the sewing machine and 2 the overhanging bracket-arm which terminates in the head 3. Projecting horizontally from the standard 1, below the arm 2, is the cylinder-bed 4. Journaled in bearings 5, 6 and 7 is the main-shaft 8 which extends within and lengthwise of the cylinder-bed 4 and terminates at the point 9, Fig. 2, about mid-way of the length of the cylinder-bed. The main-shaft 8 is formed with the crank 10 which is connected by the pitman 11 to the ball 12 on one arm 13 of a double crank fixed to the needle-bar operating rock-shaft 14 which, at its forward end, has the usual crank 15 and link-connection 16 with the reciprocating needle-bar 17 carrying the eye-pointed needles 18. The presser-foot 19 is carried, as usual, by the downwardly spring-pressed presser-bar 20.

Cooperating with the presser-foot 19 to feed the work across the cylinder 4 is the four-motion feed-dog 21 preferably actuated by the mechanism disclosed in my copending application, Serial No. 250,111, filed Janu-

ary 28, 1928, of which this application is a division.

The loopers 22, which cooperate with the needles, 18, are secured to the looper-carrier 23 which is fixed to the forward end of the 55 rocking and sliding looper-shaft 24 journaled in the cylinder-bed below the main-shaft 8. The sliding movement of the looper-shaft 24, which imparts the loop-seizing and -shedding movements to the loopers, is derived through a train of connections with the arm 25 of the double-armed lever 13, 25 fixed to the needle-bar operating rock-shaft 14. The arm 25 carries a ball 26 to which is connected the upper end of a link 27 connected at its lower end to the ball 28 on the horizontal arm 29 of a bell-crank lever 29, 30 fulcrumed on the shaft 31 in the standard. The bell-crank lever-arm 30 is forked at its upper end to embrace the split slide-block 32 which, in turn, embraces the ball-ended arm 33 fixed to the looper-shaft 24. 60 65 70 75

The needle-avoiding movement of the loopers 22 is produced by a rocking motion of the looper-shaft 24 which is derived from the eccentric 34 on the main-shaft. The eccentric 34 is surrounded by the split-block 35 the flat sides of which are embraced by the forked upper end of the arm 36, fixed to the looper-shaft 24. The eccentric 34 and 80 split-block 35 are long enough to accommodate the movements of the arm 36 with the shaft 24 lengthwise of the cylinder-bed.

Having thus set forth the nature of the invention, what I claim herein is:— 85

1. In a sewing machine, a frame comprising a standard, a bracket-arm, and a cylinder-bed, a main-shaft journaled in line with and extending into said cylinder-bed, a rocking and sliding looper-supporting shaft journaled in and lengthwise of said cylinder-bed below said main-shaft, operative connections between the main-shaft and looper-supporting shaft within the standard for sliding the looper-supporting shaft, an eccentric on the main-shaft within the cylinder-bed, and means embracing said eccentric for rocking the looper-supporting shaft. 90 95

2. In a sewing machine, a frame comprising a standard, a bracket-arm, and a cylin- 100

der-bed, a main-shaft journaled in line with and extending into said cylinder-bed, a rocking and sliding looper-supporting shaft journaled in and lengthwise of said cylinder-bed below said main-shaft, operative connections between the main-shaft and looper-supporting shaft within the standard for sliding the looper-supporting shaft, an eccentric on the main-shaft within the cylinder-bed, and a forked arm fixed to the looper-supporting shaft and slidably embracing said eccentric.

3. In a sewing machine, a frame comprising a standard, a bracket-arm and a cylinder-bed, a main-shaft journaled in line with and extending into said cylinder bed, a rocking and sliding looper-supporting shaft journaled in and lengthwise of said cylinder-bed, an eccentric on the main-shaft within said cylinder-bed, means embracing said eccentric for rocking said looper-shaft, a lateral arm on the looper-supporting shaft within the standard, a bellcrank lever having one of its arms forked to slidably embrace said lateral arm, and an operative connection between the main-shaft and the other arm of said bell-crank lever.

In testimony whereof, I have signed my name to this specification.

ANDREW B. CLAYTON.
